UNITED STATES PATENT OFFICE.

WILLIAM CASE, OF CHICAGO, ILLINOIS, ASSIGNOR TO THE NATIONAL MALLEABLE CASTINGS COMPANY, OF CLEVELAND, OHIO.

DESIGN FOR A BOLSTER FOR CARS.

SPECIFICATION forming part of Design No. 25,672, dated June 23, 1896.

Application filed May 12, 1896. Serial No. 591,302. Term of patent 14 years.

To all whom it may concern:

Be it known that I, WILLIAM CASE, of Chicago, in the county of Cook and State of Illinois, have invented a new and original Design 5 for Bolsters for Cars, of which the following is a full, clear, and exact description, reference being had to the accompanying drawings, forming part of this specification, in which—
10 Figure 1 is a perspective view of a bolster embodying my design, and Fig. 2 is a bottom plan view.

The design consists in a bolster for cars, having substantially the form shown in the accompanying drawings and herein described. 15

The bolster 2 is hollow, inclosed by bottom, top, and side members, which extend continuously from end to end of the bolster.

The bolster tapers in thickness from the middle portion toward the ends. 20

I claim—

The design for bolsters for cars substantially as herein shown and described.

In testimony whereof I have hereunto set my hand.

WILLIAM CASE.
